SHOWER BATH ATTACHMENT

Filed April 6, 1931

INVENTOR

Albert Claypoole,
Wm. Leo.

ATTORNEY

UNITED STATES PATENT OFFICE

ALBERT CLAYPOOLE, OF FINDLAY, OHIO

SHOWER BATH ATTACHMENT

Application filed April 6, 1931. Serial No. 528,147.

This invention relates to needle spray or shower bath attachments for baths.

A primary object of the invention is to provide a shower or spray attachment adapted to be connected with the faucets of the tub and to be mounted on the tub to travel back and forth and to extend around the bather when in sitting posture in the tub, which is movable to so position the spray apertures that they will discharge on various parts of the bather's body at will; and which does not require the use of a curtain.

Another object of the invention is to so shape the water carrying tube or pipe that it will extend around the body of the wearer when in sitting position in the tub and spray water onto him without splashing or sprinkling it outside of the tub.

Another object is to so construct an attachment of this character that by pressing down on a suitable handle the water distributing tube may be raised so as to spray water onto the neck and shoulders or any other part of the body at will.

In carrying out these objects, the invention is susceptible of a wide range of modification without departing from the spirit or sacrificing any of the advantages of the claimed invention; there being shown in the drawing for illustrative purposes a preferred and practical form, in which;

Figure 1 represents a perspective view of a bath tub with this improved spray attachment shown applied ready for use;

Fig. 2 is a top plan view of the spray attachment detached;

Fig. 3 is a detail transverse section taken on the line 3—3 of Fig. 1; and

Fig. 4 is a longitudinal section taken on the line 4—4 of Fig. 2; showing the device in position on a tub.

In the embodiment illustrated, the shower attachment 10 constituting the invention is shown applied to a bath tub 1 which may be of any desired character being here shown rectangular with a rim 2 around the edges thereof on which the attachment is designed to travel in a manner presently to be described. A common discharge spout 3 for the hot and cold water is shown to which the

attachment is designed to be connected, the controlling faucets 4 of which are conveniently located for manipulation by the bather.

The shower attachment 10 is made in the form of a substantially U-shaped loop 11, the legs 12 and 13 of which are arranged closer together than the sides of the body portion and positioned parallel with each other as shown clearly in Fig. 2. This loop-shaped member 11 is composed of a tube of any suitable material provided on its inner face with a plurality of longitudinally spaced perforations 14 through which the water passes in the form of spray as shown at 15. Extending laterally from the outer faces of the legs 12 and 13 are two rollers 16 and 17 mounted to revolve on spindles 18 and designed to rest and travel on the rim 2 of the tub which operates as a track for the attachment.

One end of the pipe or tube 11 is closed as shown at 19 while the other end is open and is equipped with a nipple 20 with which is designed to be connected a flexible tube or hose 21, the other end of which is engaged with the supply nozzle 3.

Extending laterally inward from the leg 12 is a handle or finger 22 which may be manipulated either by the hand of the bather or by his knee for tilting the tube 11 so that the water may be caused to strike on the neck and shoulders of the bather without wetting his hair and if desired the loop may be raised further so that the head may be washed.

The advantage of an attachment of this character is that it permits the bather to take a shower while sitting down thereby eliminating all possibility of slipping which frequently occurs when taking a standing shower. The faucets are within easy reach of the bather so that the head will not get wet when reaching for a faucet as often happens when taking a standing shower.

The loop-shaped member 11 is of a diameter to conform to the inner diameter of the tub in connection with which it is used so that all danger of water splashing outside the tub is prevented. The mounting of the rollers on the rim 2 of the tub avoids the necessity of any auxiliary fastening member and when not

in use the device may be disconnected from the faucet 3 and placed in any desired location.

By arranging the spray apertures 14 throughout the length of the inner face of the tube or loop 11 the water will be sprayed on all parts of the body simultaneously without necessitating moving of the person in the tub as is required with a standing shower.

10 Without further description it is thought that the features and advantages of the invention will be readily apparent to those skilled in the art, and it will, of course, be understood that changes in the form, proportion and minor details of construction may be resorted to, without departing from the spirit of the invention or its scope as claimed.

I claim:

1. A shower bath attachment comprising a 20 spray tube of substantially U-shaped form with water discharge apertures on its inner face around the entire length thereof, spindles extending laterally outward from the legs of said tube, rollers mounted on said 25 spindles and adapted to travel on a bath tub rim whereby the attachment may be readily shifted to suit the convenience of the user, and a flexible hose connecting said tube with a faucet.

30 2. A shower bath attachment comprising a spray tube of substantially U-shaped form with water discharge apertures on its inner face, rollers carried by the legs of said tube and adapted to travel on a bath tub rim, a 35 handle extending laterally inward from one of the legs of said tube to provide for the raising of the tube to various positions relatively to the bather, and a flexible hose for connecting the tube with a faucet.

40 ALBERT CLAYPOOLE.
